US00D758353S

(12) **United States Design Patent**
Akana et al.

(10) **Patent No.:** **US D758,353 S**
(45) **Date of Patent:** **** Jun. 7, 2016**

(54) **INPUT MECHANISM**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/525,266**

(22) Filed: **Apr. 28, 2015**

Related U.S. Application Data

(63) Continuation of application No. 29/431,844, filed on Sep. 11, 2012, now Pat. No. Des. 728,528.

(57) **CLAIM**

The ornamental design for an input mechanism, as shown and described.

DESCRIPTION

FIG. 1 is a front perspective view of an input mechanism showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the Figures show portions of the input mechanism that form no part of the claimed design.

1 Claim, 5 Drawing Sheets
